UNITED STATES PATENT OFFICE

ELMER E. LEDBETTER, OF DETROIT, MICHIGAN, ASSIGNOR TO EVER HOT HEATER COMPANY, OF DETROIT, MICHIGAN, A CORPORATION OF MICHIGAN

OVEN THERMOSTAT

Application filed May 9, 1927. Serial No. 190,023.

The invention relates to thermostats and more particularly to that type of thermostat adapted for use in regulating the temperature of ovens and the like.

5 One of the principal objects of the invention is to obtain a valve mechanism directly actuated by the longitudinal expansion and contraction of the thermostat without levers or other devices for obtaining 10 mechanical advantage, said valve mechanism being provided with means for adjusting the same to the desired temperature with extreme accuracy, the arrangement being such that the device may be set to any pre- 15 determined temperature within the normal range of oven temperatures and will operate to maintain said temperature within narrow limits of fluctuation.

Another object is to provide rotatably ad- 20 justable means for setting the thermostatically actuated valve, said means being operable by substantially a full revolution thereof in order to regulate the temperature between the upper and lower limits of the 25 normal range of oven temperatures.

Another object is to provide a thermostat in which the valve mechanism is arranged outside of the oven walls, and the pipe connections leading to the burner are attached 30 to the device within the oven walls.

A further object is to provide a device, which when mounted on the oven, requires only a single aperture in the oven wall, the pipe connections being concealed within the 35 oven and attached to the portion of the device within the oven.

These and other objects are attained by my invention, several embodiments of which are illustrated in the accompanying drawings, wherein—

Figure 1 is a longitudinal section through the thermostat;

Figure 2 is an elevation of the regulating end thereof;

45 Figure 3 is a transverse section on the line 3—3 of Figure 1;

Figure 4 is a similar section on the line 4—4 of Figure 1;

50 Figure 5 is a section on the line 5—5 of Figure 1;

Figure 6 is a side elevation of the rotatable housing and casing;

Figure 7 is a transverse section on the line 7—7 of Figure 1;

Figure 8 is a longitudinal section of a 55 modified construction;

Figure 9 is a transverse section on the line 9—9 of Figure 8;

Figure 10 is a longitudinal section through another modified construction.

Referring first to the embodiment of the invention illustrated in Figures 1 to 7, the thermostatic device comprises a fixed casing or body 1 arranged within the oven, a valve mechanism 2 extending from said body to the outside of the oven and a thermostat 3 extending from the body 1 in the opposite direction and located within the oven.

The thermostat 3 comprises two elements having different coefficients of expansion, 70 the outer tubular member 4 which is permanently secured to the body 1 at 5, and the inner rod 6 arranged within the tube 4 and extending through a longitudinal aperture in the body 1 into the rotatable housing 2. 7 is a cap permanently secured to the tube 4 and provided with internal threads 8 for adjustably securing the inner rod 6. Any suitable materials may be used for the parts of the thermostat, but in the 80 preferred construction the outer tube 4 is of copper, the inner rod 6 is of steel and the body 1 is of brass. These materials are practical from a production standpoint, and there is a sufficient differential in the 85 coefficients of expansion of the steel on the one hand and the copper and brass on the other hand to provide for the necessary movement of the valve mechanism when constructed in accordance with my invention.

90 However, it will be understood that other suitable materials might be employed providing the proper differential expansion is obtained and the materials are capable of being assembled together in the proper relationship.

The body 1 has secured therewithin a tube 9 surrounding the steel rod 6 forming an annular passageway 10. The tube 9 also forms with the surrounding portion of the 10

casing an annular passageway 11 which leads into an enlarged chamber 12. The portion of the casing or body containing the chamber 12 is of substantially circular cross section, and is arranged eccentrically to the tube 9 so that the greater portion of the chamber is arranged below the tube. At the lower side of this eccentric portion of the body there are provided two threaded 5 apertures, 13 and 14, the former constituting the inlet aperture and extending through the tube 9 into the annular passageway 10, and the latter constituting an outlet port and extending into the passageway 15. The 10 passageway 15 extends longitudinally of the body into the chamber 12. The threaded apertures 13 and 14 are preferably arranged at an angle of 90° so that the inlet and outlet pipes 16 and 17, which are connected thereto, will extend downwardly within the 15 oven.

The valve mechanism 2 comprises a rotatable valve seat 20 to which is secured a valve housing cap 21 forming the valve chamber 22. The valve seat 20 is adjustably secured to the body 1 by the threaded extension 23 which surrounds the tube 9 forming a continuation of the passageway 11. 24 is a disk valve longitudinally slidable on the tube 9 and provided with an annular knife-edge portion 25 for engaging the valve seat 20. The valve 24 is at all times urged toward its seat by the spring 26 between the valve and the housing cap 21. 25 The valve 24 has a central head portion 27 surrounding the reduced end of the thermostatic rod and engageable with the annular shoulder 28 of the latter. The head is provided with radial apertures 49 extending 30 through the side walls thereof affording communication between the passageway 10 and the valve chamber 22. The reduced end of the rod 6 is axially movable within an apertured boss 29 on the housing cap and 35 is provided with a slotted end 30 for engaging a pin 31 carried by said boss.

For rotating the housing 21 there is provided a hand wheel 32 clamped to the housing by a cap 33 and screw 34. The hand 40 wheel is held from rotation relative to the housing by the heads of the screws 35 which engage recesses in the hand wheel. The screws 35 also serve to secure the valve seat and the housing cap together. The temperature calibrations are marked upon the outer 45 circumference of the rotatable housing and the reading is indicated by means of a pointer 36 extending from a cover plate 37 secured to the body 1. In the illustrated construction the calibrated scale is marked upon a strip 38 bent into annular form and held in position by clamping the same between the valve seat 20, and the hand wheel 32. Each of these members is provided with an 50 annular groove 39 and 40 respectively, for

receiving the edges of the strip and the ends of the strip are arranged within an H block 40. With this arrangement the calibrated strip together with the H block may be rotatably adjusted on the housing to the desired position and afterwards clamped by the hand wheel 32. The H block 40 is preferably extended sufficiently to engage the pointer 36, thus constituting a stop for preventing more than one revolution of the 55 housing.

It is usual to provide a by-pass around the thermostatic valve so that a small quantity of gas sufficient to maintain a pilot light will at all times be delivered irrespective of the setting of the valve. In my construction the by-pass is arranged in the body 1 between the inlet passageway 10 and the outlet passageway 15. A radial bore 46 is drilled through the body 1 and a needle valve 47 is inserted therein, being adjustable by the rotation of the threaded head 48. The tube 9 has drilled therein an orifice in alignment with the radial bore and of such size as to cooperate with the end of the 60 needle valve to produce the proper regulation of the gas.

The thermostatic device is mounted on the oven by inserting the body 1 through an aperture 43 in the outside oven wall 42, the body being suitably secured within the oven. In the usual construction of ovens an inner wall 44 is provided, and also an inner-lining 45. My construction is adapted to be inserted within the oven so that the casing or body 1 is located between the outer oven wall and the inner-lining. The conduits 16 and 17 leading from the body may therefore be carried downward inside of the outer oven wall and the conduit 17 may be connected to the oven burner without being brought outside of the oven walls. The other conduit 16 may be connected to the supply line at a suitable point less conspicuous than the location of the thermostat. The eccentric relation of the main portion of the body 1 with reference to the thermostat enables the placing of the device close to the top of the oven so that the thermostat may extend inwardly in the channel formed in the top of the oven inner-lining in the usual manner.

It will be noted that the gas passes from the inlet conduit 16 through a radial passageway into the annular passageway 10, from whence it travels axially of the tube 9 and radially outwardly through the ports 49 to the valve chamber 22. From the valve chamber the gas passes through the annular orifice between the valve and the valve seat to the outer annular passageway 11, from whence it is delivered axially to the chamber 12 and port 15, then radially through the outlet orifice 14 and outlet conduit 17 to the burner.

As heretofore mentioned, one of the principal advantages of the construction is that it permits very accurate regulation of the temperature by the provision of a directly actuated valve connected to the thermostat. With such a construction the maximum movement of the valve due to the differential longitudinal expansion of the thermostatic elements is comparatively small, and yet it is necessary to provide means for adjusting the thermostatic elements relative to each other so that the valve will be adjusted to maintain any desired temperature within the range of oven temperatures. It is evident that if the operating handle turns through substantially a full revolution between the upper and lower temperatures, it must be adjustably connected to the thermostat to impart only a minute axial movement thereto for each position of rotative adjustment. In the device illustrated in Figure 1 this is accomplished by means of differential threads. Thus the threads 23 are of slightly different pitch than the threads 8 so that upon rotation of the hand wheel, while both the housing 21 and the thermostatic rod 6 are axially advanced relative to the body, the relative movement between the valve seat 20 and the valve 24 is only a fraction of the total movement. This enables the use of standard threaded connections for both the rotatable housing and the thermostatic rod, and yet permits a very fine adjustment between the valve and valve seat during a complete revolution of the housing.

There are other methods of obtaining the fine adjustment between the valve and valve seat, and in Figure 10 I have illustrated a modified construction which accomplishes the same results in a different manner. In this construction the valve seat 20^a is non-adjustably secured to the body 1 and is preferably made integral therewith. The valve housing 21^a by being secured to the valve seat 20^a is therefore non-adjustably mounted with respect to the body 1 and serves merely to enclose the valve 24 in a position outside of the oven wall 42. The thermostat is similar in construction to the one previously described, except that the cap 22^a instead of being permanently secured to the outer tube 3 is adjustably secured thereto by the threads 49. The steel rod 6 is also adjustably secured to the cap 22^a by the threads 8 which are of a slightly different pitch than the threads 49. The adjustment of the thermostat for different temperature settings may be obtained by rotation of the cap 22^a, the cap being axially advanced relative to the tube 3 and the rod 6. By choosing the proper differential between the pitches of the threads 49 and 8 a rotative adjustment of the cap 22^a through a complete revolution will adjust the valve 24 relative to the seat 20^a the desired amount to maintain the tem-

perature of the oven at the desired point within the maximum range. For rotating the cap 22^a it is preferably provided with an extension 50 leading through the oven wall 51 at the opposite side from the valve mechanism, and having secured at its outer end a suitable hand wheel 52. The periphery of the hand wheel may be provided with calibrations which cooperate with a fixed pointer 53 secured to the oven wall. 75

Figures 8 and 9 illustrate another modified construction wherein the adjustment of the valve is obtained by the use of a single threaded connection. In this construction the valve housing 21^a is similar to that shown in Figure 10 and is non-adjustably secured to the body 1. The thermostat is provided at its outer end with a cap 54 permanently secured to the outer tube 3 in the same manner as illustrated in Figure 1, and has an extension 55 internally threaded at 56 for receiving the threaded end 57 of the inner rod 6. In order that a full rotation of the rod 6 may be employed for adjusting the thermostat within the range of oven temperatures without imparting too great an axial advancement to the valve 24, it is necessary that the threads 56 and 57 be very fine, such for example as seventy-two threads to the inch. It is also evident that the use of such fine threads necessitates the construction of a special type of threaded connection, which will not wear and will not develop play or lost motion. The preferred construction of the threaded connection is obtained in the following manner. 95

The outer end of the extension 55 is longitudinally slotted in several places as indicated at 58, and the segments 59 produced by the slots are compressed inwardly by means of a compression nut 60. This nut has tapered threads 61 which engage corresponding tapered threads 62 on the exterior of the extension 55. In the manufacture of the cap 54 and the rod 6 these parts are assembled in threaded engagement, and the compression nut 60 is placed in position on the extension 55 and rotated until the segments 59 are forced into firm frictional engagement with the threaded end of the rod 6. The rod 6 is then rotated, first in one direction and then the other direction, to lap the threads 56 and 57 and remove any inaccuracies in the threads. During the lapping process the cap 60 is periodically advanced on the tubular extension 55 to take up any play resulting from the wearing of the threads, and by repeated working of the threads in this manner it is possible to obtain a threaded engagement of the cap 54 and rod 6 which is free from any lost motion and is very accurate. When it is realized that the rotative adjustment of the rod 6 in the cap 54 for setting the thermostat to its upper and lower temperature lim- 130

its is only one complete revolution while the two parts are connected together by a plurality of thread convolutions, it will be readily apparent that the method outlined above 5 will insure the formation of a very accurate adjustment means for the thermostat. If any lost motion develops in the threaded connection after the thermostat is in commercial use this may be eliminated by further advancing the compression nut 60 on the cap, thereby increasing the compression of the segments 59. It is preferable that the inner end of the nut 60 be threaded onto the extension 55 sufficiently so as to entirely cover the slots 58 and also cover a portion of the unslotted cap, so that a gas-tight joint will be made.

For adjustably rotating the rod 6 there is provided an adjusting wheel 63, preferably mounted on an extension 64 of the rod 6 which projects through the valve housing cap 21^a. The extension 64 is caused to have a tight seal with the housing cap 21^a in any suitable manner, such for instance as providing the packing 65 and the packing nut 66. The hand wheel 63 is keyed or otherwise secured to the extension 64 and is preferably provided with an annular flange 67 surrounding the housing cap 21^a. The calibrations are marked upon the outer periphery of the flange 67, and the setting of the thermostat is indicated by a pointer 68 secured to the valve seat 20^a and extending over the flange 67.

In all of the constructions described above, I have illustrated thermostatic devices which are capable of being used as oven regulators and will accurately control the temperature of the oven within the usual 35 range of oven temperatures, which is ordinarily from 250 degrees to 550 degrees F. The constructions are all adapted to be mounted on an oven without requiring any external piping, since the inlet and outlet gas conduits are connected to the portion 40 of the fixed casing arranged within the oven walls. The valve mechanism and the regulating mechanism is in each case arranged outside of the oven walls, thus avoiding the excessive heat. The constructions are also 45 such that the valve mechanism is readily accessible and can be removed without affecting the calibration of the thermostat.

As heretofore mentioned, the preferred 55 materials for the thermostat are copper or brass for the more expansible element and steel for the less expansible element. It has been found that ordinary steel is well suited for the rod 6, since its coefficient of expansion is substantially constant throughout 60 the range of oven temperatures. In the modification illustrated in Figure 8 it may be desirable to substitute stainless steel for ordinary steel in order to insure that no 65 corrosion takes place in the threads 57

where extreme accuracy must always be maintained to insure the accuracy of the thermostat.

What I claim as my invention is:

1. An oven regulator comprising a valve 70 seat, a valve cooperating therewith, an expansible tube having one end connected to said valve seat, a less expansible rod connected to the other end of said tube, said rod being operably connected to said valve to directly actuate the latter by differential longitudinal movement of said tube and rod, and rotatably adjustable means operable through substantially a full revolution for setting said valve relative to said seat to 75 correspond to the normal range of oven temperatures, said means including two sets of threads of different pitch adapted for simultaneous adjustment.

2. An oven regulator comprising a fixed 80 casing, having inlet and outlet ports arranged within the outside wall of the oven, a valve mechanism arranged outside of said wall, thermostatic means for operating said valve mechanism and means outside of said wall for setting said valve mechanism to operate at varying temperatures.

3. An oven regulator comprising a fixed 85 casing within the outside wall of the oven, a valve housing outside of said wall, inlet and outlet conduits connected to said casing within the said outside wall, a valve within said valve housing, separate passageways leading from said inlet and outlet conduits to said valve housing on opposite sides of said valve, a thermostat operatively connected to said valve and means for adjustably setting said thermostat to close said valve at varying temperatures.

4. An oven regulator comprising a fixed 90 casing, having inlet and outlet ports therein, a valve housing, a valve within said housing, a tubular member connecting said valve housing and said casing, a second tubular member within said first tubular member, forming between the same a passageway 95 connecting one of said ports with the valve housing on one side of said valve, the interior of said second tubular member forming a passageway connecting the other port with the valve housing on the other side of said valve.

5. An oven regulator comprising a casting 100 within the outside wall of the oven, having inlet and outlet ports therein, a valve housing outside of said oven, a tubular member extending through the oven wall connecting said casing and said valve housing, a second tubular member extending from 105 said casing through said first tubular member to said valve housing, a disk valve within said housing sleeved on said second tubular member and a thermostat for longitudinally adjusting said valve relative to said housing.

6. An oven regulator comprising a hollow casing within the outside wall of the oven, having a pair of fuel ports therein, an expandible thermostatic tube secured to and projecting from one end of said casing, a second tube projecting from the opposite end of said casing, a valve housing carried by said second tube, a thermostatic member having a smaller coefficient of expansion than 5 said thermostatic tube, said thermostatic member having one end thereof secured to said expandible tube and having the other end extending through said casing to said valve housing; a third tube projecting from 10 said casing into said valve housing forming separate passageways interiorly and exteriorly thereof, communicating respectively with said fuel ports, a disk valve within said housing slidable on said third tube and operatively connected to said thermostatic member. 15
7. An oven regulator comprising a hollow casing having a pair of fuel ports therein, a tubular thermostatic member secured to and 20 projecting from one end of said casing, a second tube projecting from the opposite end of said casing, a valve housing carried by said second tube, a third tube projecting from said casing into said valve housing 25 forming longitudinally extending passageways interiorly and exteriorly thereof, a disk valve within said housing slidable on said third tube, a thermostatic rod operatively connected to said valve and adjustably threadedly connected to said thermostatic tube and rotatably adjustable means 30 operable through substantially a full revolution for longitudinally adjusting the thermostatic rod with respect to said thermostatic tube. 35
8. In an oven regulator the combination of a fixed casing adapted to be secured within the outside wall of an oven, and having inlet and outlet fuel ports adapted 40 to be connected to a fuel line within the oven, a valve housing, a tubular member connecting said casing and valve housing, a valve within said housing and means for forming two separate passageways within 45 said tube leading respectively to said valve housing on opposite sides of said valve. 50
9. An oven regulator comprising a hollow body adapted to be secured within the outside wall of the oven, an expandible tube projecting from said body, a less expandible rod connected to said tube and extending through said body, a valve housing projecting oppositely from said tube and provided 55 with a tubular extension connecting the same to said hollow body, a valve within said housing operatively connected to said thermostatic rod and means for forming two 60 separate passageways through said tubular extension into said valve housing, said 65 passageways communicating respectively on opposite sides of said valve. 70
10. An oven regulator comprising a hollow casing, a valve housing connected to and longitudinally spaced from said casing, a gas conduit within said hollow casing extending toward said valve housing, a disk valve longitudinally movable in said housing, said valve having a passageway therethrough and means connecting said gas conduit and valve for maintaining a passageway between the gas conduit and the valve housing during the movement of said valve. 75
11. An oven regulator comprising a valve housing having an annular seat, a disk valve axially movable within said housing and provided with an aperture therethrough, a gas conduit projecting from said housing and communicating therewith between said seat and one side of said valve, a second gas conduit connected to said valve to maintain communication through said aperture to the portion of the valve housing on the opposite side of the valve, and a thermostatically operated member for axially moving said valve relative to said seat. 80
12. An oven regulator comprising a valve housing having an annular seat, a disk valve axially movable within said housing and provided with an aperture therethrough, a gas conduit projecting from said housing and communicating therewith between said seat and one side of said valve, a second gas conduit telescopically engaging said valve and communicating through said aperture to the portion of the valve housing on the opposite side of said valve, and a thermostatically operated member for axially moving said valve relative to said seat. 85
13. An oven regulator comprising a fixed casing having inlet and outlet ports arranged within the outside wall of the oven, a valve mechanism arranged outside of said wall, thermostatic means for operating said valve mechanism, said thermostatic means extending through the portion of the casing having the inlet and outlet ports therein, and means outside of the outside walls of the oven operable through substantially a full revolution for adjustably setting said valve mechanism to operate at varying temperatures between the upper and lower limits of the normal range of oven temperatures. 90
14. An oven regulator comprising a fixed casing within an outside wall of the oven, a valve housing outside of said wall, inlet and outlet conduits connected to said casing within said outside wall, a valve within said valve housing, separate passageways leading from said inlet and outlet conduits to said valve housing on opposite sides of said valve, a thermostat operatively connected to said valve comprising two longitudinally extending members of different expansion 120
- 125
- 130

properties, said thermostat being arranged in the portion of said fixed casing having the inlet and outlet ports therein, and means operable through substantially a full revolution for adjustably setting said thermostat to close said valve at any temperature between the upper and lower limits of the normal range of oven temperatures.

15. An oven regulator comprising a valve 10 housing having a valve seat, a valve within said housing, an expansible tubular member extending from said valve housing, a less expansible member having one end connected to said tubular member and the other 15 end operatively connected to said valve, resilient means cooperating with said operative connection to move the valve relative to said valve seat upon change in temperature, an operating handle outside of said oven wall rotatable between limiting positions arranged substantially a full revolution apart, threaded means operable by said handle for variably adjusting the setting of said valve relative to said seat and means 20 cooperating with said threaded means to cause said valve to seat at the upper and lower limits of the normal range of oven temperatures corresponding respectively to the aforesaid opposite limiting positions of 25 rotative adjustment of said handle when the oven temperature is at or above the temperature at which said handle is set.

16. An oven regulator comprising a valve 30 housing having a valve seat, a valve within said housing, an expansible non-ferrous member extending from said valve housing, a less expansible ferrous member having one end connected to said expansible member and the other end operatively connected to 35 said valve, resilient means cooperating with said operative connection to move the valve relative to said valve seat upon change in temperature, an operating handle outside of said oven wall rotatable between limiting positions arranged substantially a full revolution apart, threaded means operable by said handle for variably adjusting the setting of 40 said valve relative to said seat and means cooperating with said threaded means to cause said valve to seat at the upper and lower limits of the normal range of oven 45 temperatures corresponding respectively to the aforesaid opposite limiting positions of rotative adjustment of said handle when the oven temperature is at or above the temperature at which said handle is set.

17. An oven regulator comprising a valve 50 housing having a valve seat, a valve within said housing, an expansible bronze member 55 extending from said valve housing, a less expansible steel member having one end connected to said expansible member and the other end operatively connected to said valve, resilient means cooperating with said 60 operative connection to move the valve rela-

tive to said valve seat upon change in temperature, an operating handle outside of said oven wall rotatable between limiting positions arranged substantially a full revolution apart, threaded means operable by said handle for variably adjusting the setting of said valve relative to said seat and means cooperating with said threaded means to cause said valve to seat at the upper and lower limits of the normal range of oven 70 temperatures corresponding respectively to the aforesaid opposite limiting positions of rotative adjustment of said handle when the oven temperature is at or above the temperature at which said handle is set.

18. An oven regulator comprising a valve 75 housing having a valve seat, a valve within said housing, a bronze member extending from said valve housing, a steel member connected between said bronze member and said valve, resilient means cooperating with said steel member to move said valve relative to said valve seat upon change in temperature, an operating handle rotatable between limiting 80 positions substantially a full revolution apart and differentially movable threaded means rotatable by said operating handle, said threaded means being interposed between said valve housing and said valve.

In testimony whereof I affix my signature.
